FRITZ HERLACH, OF DUSSELDORF, GERMANY, ASSIGNOR TO RHEINISCHE METALL-WAAREN- UND MASCHINENFABRIK, OF DUSSELDORF, GERMANY, A CORPORATION OF GERMANY

AUTOMATIC FIREARM WITH SLIDING BARREL AND LOCKED BREECH

Application filed October 23, 1929, Serial No. 401,867, and in Germany September 21, 1928.

In a particular type of breech piece with rotary ribs for automatic firearms with sliding barrel, the breech piece consists of a body portion guided rectilinearly in the casing of the weapon, and with a rotatable head portion carrying the devices locking it with the barrel, the head portion being rotated by means of a torsion spring into the locking position. The breech is unlocked during the recoil of the barrel by a cam on the head of the breech piece, which in co-operation with a circularly formed guiding groove on a fixed portion of the weapon, for example on the casing, rotates it into the unlocked position relatively to the body portion of the breech piece, at the same time stressing the torsion spring. The head portion of the breech retains this position until the end of the forward movement of the breech piece, when the latter is again released by the torsion spring which is kept in the stressed position along the guiding groove and rotates the head portion and locks it with the barrel.

This device has, however, the drawback that the guiding members of the two part breech piece, after the breech has been unlocked during the whole further forward and backward movement, are pressed by the stressed torsion spring against the guides on the casing of the weapon. Considerable additional frictional resistances are thus produced which retard the movement of the breech piece and thereby reduce the rapidity of firing.

The invention obviated this drawback by the provision of a locking device between the two parts of the breech piece, which, after the head portion of the breech has been unlocked from the barrel and, therefore, after the spring has been stressed, is automatically inserted and prevents any relative rotation between the two parts of the breech and the spring from exerting any outward force. The guiding members of the breech piece during the further succeeding backward and forward movements can now slide unhindered in the guiding groove of the casing without being stressed by the spring. Only when the breech piece has moved into its front end position is the locking released under the control

of a stationary portion of the weapon; the spring can now rotate the head portion of the breech into the locking position with the barrel. Besides the increase of the rapidity of firing in consequence of the reduction of the frictional resistance, the invention enables a simpler construction of the guiding groove in the casing of the weapon to be obtained. The groove need not then have the circular form which is difficult to manufacture. It is sufficient to provide a simple recess in the casing with a single inclined surface for unlocking the head of the breech, so that the controlling switch necessary in the previously known guiding groove is also no longer required.

An example of a construction according to the invention is shown in the accompanying drawings.

Figure 1 is a longitudinal section through the still unlocked breech parts shortly before the end of its forward movement.

Figure 2 is a cross-section through the breech seen in the direction A—A of Figure 1.

Figure 3 is a cross-section seen in the direction B—B.

Figure 4 is a section on the line C—C of Figure 2.

The barrel *a* mounted so as to be longitudinally displaceable in the casing *b* of the weapon, can be locked with the two part breech piece *c*₁, *c*₂ by a bayonet joint. The breech consists of a body portion *c*₁, guided rectilinearly in the casing *b* of the weapon, and a head portion *c*₂ carrying locking ribs *c*₃ and *c*₄ rotatable relatively to the part *c*₁. Both parts *c*₁ and *c*₂, are secured by a bayonet joint *c*₄, against separation from the barrel during the relative rotation, taking place in the normal manner in the course of the firing period, but which separation occurs later against the action or with the aid of a torsion spring *e* inserted between the two parts. An arm *c*₅ arranged on the part *c*₂, serving also as a hand grip, projects outwardly through a recess of the casing *b* of the firearm. A bolt *c*₆, displaceable to a limited extent in the arm *c*₅, is disposed opposite to the front surface of the recess of the casing *b* and cooperates in a

nanner described further later with a locking bolt c_7 projecting out of the part c_1 .

In the description of the action, it is assumed that the gun has just been fired. By the recoil of the powder gases, the breech, of which the head c_2 takes up the position shown dotted in Figure 2 and is locked with the barrel a is at first impelled rearwards with the barrel until the arm c_5 encounters an inclined surface b_1 of the recess of the casing b . The part c_2 is thereby rotated relatively to the rectilinearly controlled part c_1 , whereby the breech c_1, c_2 is unlocked from the barrel a and the locking spring e is stressed. During the last part of the rotation imparted to the part c_2 , an inclined surface c_8 (Figure 4), formed in the arm c_5 , encounters a locking bolt c_7 projecting, under the action of a spring, from the part c_1 and presses it back, until, when the breech has been completely unlocked, the bolts c_6, c_7 of the two parts c_1, c_2 of the breech come into register, and the bolt c_7 enters the arm c_5 , thereby displacing the bolt c_6 to some extent forward. The whole force of the locking spring e is now confined to the locked parts c_1, c_2 of the breech. On the further rearward and later forward movement of the breech piece, for the purpose of discharging the fired cartridge and for introducing a new cartridge, the guiding members of the two parts c_1, c_2 of the breech are not subjected to the action of the spring e . Shortly before the breech piece reaches its front end position (Figure 1) the bolt c_6 is forced back by engaging with the front surface of the recess of the casing b and thereby displaces the bolt c_7 rearwards from the part c_2 , so that the means previously preventing the relative rotation of the two parts c_1, c_2 of the breech are again removed. The spring e is released and rotates the part c_2 into its former position in which it was locked to the barrel.

I claim:

1. Automatic firearm with a sliding barrel and two part breech piece comprising in combination a body portion of said breech piece guided rectilinearly in the casing of said weapon, a head portion of said breech piece, a torsion spring inserted intermediately and controlling the rotation of said head portion of said breech piece, locking means intermediate the two parts of the said breech piece, which are automatically inserted on the recoil of the said breech piece, after the said head portion has been rotated and unlocked from the barrel of the weapon against the resistance of the said spring.

2. Automatic firearm with a sliding barrel and two part breech piece comprising in combination a body portion of said breech piece guided rectilinearly in the casing of said weapon, a head portion of said breech piece, a torsion spring inserted intermediately and controlling the rotation of the said head por-

tion of said breech piece, locking means intermediate the two parts of the said breech piece, which are automatically inserted on the recoil of the said breech piece after the said head portion has been rotated and unlocked from the barrel of the weapon against the resistance of the said spring, said locking means connecting the two parts of the breech piece against relative rotation, which locking means is again automatically ejected.

3. Automatic firearm with a sliding barrel and two part breech piece comprising in combination a body portion of said breech piece, means for rectilinearly guiding said breech piece in the casing of said weapon, a head portion of said breech piece, a torsion spring inserted intermediately and controlling the rotation of the said head portion of the said breech piece, locking means intermediate the two parts of the said breech piece, which are automatically inserted on the recoil of the said breech piece after the said head portion has been rotated and unlocked from the barrel of the weapon against the resistance of the said spring, said locking means connecting the two parts of the breech piece against relative rotation, means for automatically ejecting said locking means and means for returning the head portion of the breech piece into the position in which it is again locked with the barrel.

In testimony whereof I have affixed my signature.

FRITZ HERLACH.
